TYING MACHINE

Stephen L. Matousek, Dearborn, Mich.

Application November 11, 1936, Serial No. 110,269

4 Claims. (Cl. 17—34)

This invention relates to automatic tying machines, and constitutes an improvement upon the machine disclosed in my copending application Serial No. 39,945, filed September 3, 1935, which 5 has matured into Patent No. 2,096,972, dated October 26, 1937.

An important object of the present invention is to simplify and to render more compact the construction of such tying machines, to provide a 10 machine adapted to tie a simpler yet equally effective knot, and to provide for such machines improved stock feeding mechanism, and an improved needle and shuttle construction.

Other objects and advantages will be apparent 15 from the following description wherein reference is made to the accompanying drawings illustrating a preferred embodiment of my invention and wherein similar reference numerals designate similar parts throughout the several views.

20 In the drawings:

Figure 1 is a side elevational view of a tying machine incorporating the principles of the present invention, parts being broken away and shown in section.

25 Figure 2 is a top plan view thereof, parts also being broken away.

Figure 3 is a front elevational view, taken as indicated by the arrow 3 of Figure 1, the feed mechanism and supporting means being broken 30 away.

Figure 4 is a horizontal section taken substantially on the line 4—4 of Figure 1, and looking in the direction of the arrows.

Figure 5 is a horizontal section taken substantially on the line 5—5 of Figure 1, and looking in the direction of the arrows.

Figure 6 is a detailed section taken substantially on the line 6—6 of Figure 2 and looking in the direction of the arrows.

40 Figure 7 is a detailed section of the needle construction.

Figure 8 is a fragmentary detailed view of the mutilated bevel gear and pinion drive for the shuttle rotating mechanism.

45 Figure 9 is a detailed fragmentary elevational view of the planetary gearing for driving the cord-carrying and cutting head.

Figure 10 is a fragmentary detailed side elevational view of the cutting head.

50 Figure 11 is a front elevational view of the cutting head, showing appurtenant supporting and operating portions in section.

Figure 12 is a detailed sectional view, showing the shuttle tube in section and illustrating the 55 cord gripping means, taken substantially on the

line 12—12 of Figure 4, and looking in the direction of the arrows.

Figures 13, 14, 15, 16, 17 and 18 are diagrammatic views showing the work and the tying cord, as well as the needle, shuttle and head portions, 5 progressively showing the positions they assume in performing a tying operation.

Figure 19 is a fragmentary elevational view of a tie completed and partly tightened upon the stock, and

10 Figure 20 is an end view of the nose of the shuttle, taken substantially on the line 20—20 of Figure 13 and looking in the direction of the arrows.

15 Referring now to the drawings, the main frame of my improved machine comprises a vertically disposed plate 21 supported upon legs 22. Bearing brackets 24 projecting horizontally from frame plate 21 carry the vertically disposed main shaft 25, drivable by any suitable source of power, such, 20 for example, as the electric motor 26. The work is fed downwardly through a vertically disposed work tube 20, which is preferably larger than the work, to substantially eliminate wall friction. An interchangeable gauge ring 23 centers the 25 work at the tying station, which is located at the gap 200 between the upper and lower sections of the work tube.

The motor is intended to operate constantly when the machine is in use, turning the shaft 30 through the agency of a worm 27 and worm wheel 28. The worm wheel 28 is loose upon the shaft, but rigidly secured to a sleeve 31, which also carries the drum 30, indicated as formed integrally therewith. Loose upon the sleeve between the worm wheel and the drum 30 is a disc 35, and abutting the other end of drum 30 is another drum 32, of the same size as the first, secured to the shaft to provide a virtual continuation of the cylindrical surface of drum 30. A 40 helical spring 33 is wound over both drums, acting as a clutch element to transmit the drive from the motor-driven drum 30 to the drum 32, which is attached to the shaft. The spring is at one end bent to project into disc 35, and at the other end held in the flange 36 of drum 32. Means for holding and releasing the disc at will is provided in the form of a lever 37 having an end movable into and out of the path of a lug 34 carried by the disc. The spring is so wound with 50 respect to the direction of rotation of the sleeve and drum 30 that the drag of the sleeve and drum upon the spring tends, when the disc is held, to unwrap and expand the spring, keeping it free of binding engagement with the drum, while when 55

the disc is released, the spring grips the drum, rotation of which tends to tighten it. The spring then grips both drums, and transmits the drive from one to the other, while as soon as disc 35 is again blocked, the spring is expanded and drum 30 turns freely. The work, in the form of a continuous stuffed casing, which is to be tied at intervals, is fed downwardly through the work tube 20, which is formed in independent but virtually aligned upper and lower sections, the upper section being supported by bracket 44; and the lower by brackets 45-46. The work tube assembly is carried in vertical position upon the opposite side of the frame member 21 from the main shaft 25. The work tube 20 is open at the top and bottom of the machine, the sausage casing or other work being fed into the tube from above, and after tying allowed to fall from the bottom of the tube upon or into any desired receiving receptacle or conveyor (not shown).

The feed mechanism

The work feeding mechanism, carried on top of the machine, is driven from the main shaft 25, through bevel gears as 51-52. Gear 51 is carried by an extension of the main shaft which projects above the body of the machine, while gear 52 transmits the drive to the horizontally disposed feed shaft 55. Shaft 55 is carried by brackets 53-66, the former loosely supported by post 56, which may comprise an enlarged upward extension of shaft 25. Bracket 53 is independently swingable about the axis of the main shaft, and bracket 66 rigidly but adjustably secured to the top of post 54, as by cap screw 69.

Although the main shaft rotates continuously, the work must be fed intermittently, and halted at desired intervals during which the tying operations are performed. Such intermittent feeding is effected by a feed wheel 50 having a work-holding rim provided with gripping fingers as 50A which hold the relatively soft and deformable surface of the work with sufficient firmness to insure movement of the work when the wheel is rotated. The feed wheel is carried upon the end of shaft 55 and arranged tangentially with respect to the extended axis of the work tube 20. The feed wheel is preferably formed of sheet metal, its rim having radial cuts forming the fingers 50A, which are bent laterally to the desired extent, providing in effect a notched pulley-groove in the rim of the wheel in which the work fits, and by which it is held with sufficient firmness even though passed only once over the wheel.

The feed wheel is loose upon the feed shaft, and rotation of the shaft tends to wind up or tighten a spiral spring 57, the inner end of which is secured to a driving disc 58 fast upon the feed shaft, while the other end of the spring is secured to the feed wheel. The spring constantly exerts torsion upon the feed wheel, tending to rotate it in the same direction as, and faster than, the feed shaft. A pawl 61 carried by the feed wheel (to which it is pivotally attached by a pivot pin 62), engages and travels point first over a fixed ratchet wheel 65, allowing the feed wheel to advance but one notch at a time. The pawl is forced into engagement with the ratchet by a small torsion spring 63, the ratchet being shown directly secured as by screws 72 to the flange 67 of bracket 66. The spacing of the notches determines the angular intervals at which the feed wheel stops, and accordingly fixes

the length of the links tied by the tying mechanism (presently to be described) for a given feed wheel diameter.

The spring-supporting and drive disc 58 will be seen to be larger than the ratchet 65. A pin 68 carried by the disc projects into the path of and beneath the pawl in such position that upon each rotation the pin lifts the pawl, thereby allowing the spring to advance the feed wheel, faster than the shaft 55, until the pawl catches in the next notch, where it remains, holding the wheel stationary until the pin again catches up with and lifts the pawl, releasing the wheel for another advancing movement. It will be seen that the tripping pin 68 never passes completely beneath the pawl, the spring advancing the wheel and pawl faster than the pin and feed shaft as soon as the pawl is released, and the pin again tripping the pawl upon catching up with it.

When it is desired to change the length of the tied links, it is only necessary to substitute a feed wheel of different diameter, and to re-locate shaft 55 so that the new wheel is tangential to the work tube.

For this purpose the feed wheel is removably secured to its hub 59, as by means of thumb screws 64, and retained upon the shaft 55 by a headed sleeve 75, which projects through the wheel, as well as through the drive disc, ratchet and bracket members, being interposed between all of these and the shaft. The inner end of the sleeve is split and provided with a tapered thread enabling securing and releasing it with respect to the shaft by a squeeze nut 76 located upon the other side of the bracket. When the nut is loosened, longitudinal movement is possible between the shaft and sleeve, thereby allowing sliding of the shaft 55 through the sleeve 75. Only the drive disc 58 is keyed to the sleeve 75, the remaining elements being loose with respect thereto. Ratchet 65 is fixed to the bracket flange 67, as by screws 72.

It will be seen that when the clamping nut 76 and the cap screw 69 holding bracket 66 are loosened, the entire assembly carried by the sleeve 75 is slideable longitudinally of shaft 55 as the latter swings about the vertical axis of shaft 25, the extent of the longitudinal movement of the feed assembly being controlled in its relation to angular movement of the shaft by the curvature of the curved slot 66A formed in bracket 66 to guide its movement during adjustment, so as to maintain the tangential position of feed wheels of different sizes.

The tying mechanism

The tying mechanism incorporates needle and shuttle elements, the construction of which will presently be described in detail, adapted to be reciprocated by a face cam 80 driven from the lower end of the main shaft 25 through gears 82, 83, 84. The cam encircles and is rotatable about the axis of the work tube, being carried by a sleeve or hollow shaft 81, journaled in brackets 45-46. Each face of the cam is provided with a track, one, as 86, acting to reciprocate the needle 100, and the other, as 87, driving the shuttle 115.

Two transverse horizontal slide bars 88-89, one on either side of the work tube, support slides 90-91, the former carrying the shuttle and the latter the needle. Supplementary brackets 46A and 46B, secured to plate 21, support the ends of the slide bars, and the slides 90-91 are reciprocated thereover toward and from the

work tube by the cam member 80. The shuttle slide 90 is provided with a follower 92 projecting from its under face into direct engagement with track 87 of cam 80, while needle slide 91 carries 5 an arm 93 which, as best shown in Figure 3, extends around the edge of and beneath the cam, carrying at its end a follower 94 which projects upwardly into engagement with track 86, whereby by rotation of the cam may reciprocate the needle slide. Springs as 96-97 may be arranged to 10 assist the return of the slides.

The construction of the needle element, carried by slide 91, is best shown in Figures 7 and 15. The stem or body 100 of the needle is provided with a hooked extremity, the lateral opening 101 of which is adapted to catch the cord or other tying material, while the end of the needle is inclined so that the cord may readily slide thereover and into the opening. A tube 102 surrounds the needle body, these elements being slidable with relation to each other. A coil compression spring 103 encircling the other end of the needle tends both to retract the needle into the tube, and urge the tube forwardly over the 20 needle. The tube and the needle are slidable in the supports or brackets 104-105 by which they are mounted upon the face of the slide 91, the initial position of the needle being adjustable by means of a jam nut 106 by which it may be locked 25 with respect to the threaded collar 107 which serves to slidably mount the rear end of the needle in the bracket 105, such end of the needle being threaded for engagement with the nut and collar. The collar is flanged to limit rearward 30 movement of the needle, and the needle tube, likewise, carries a collar 108 to limit its forward movement, the setting of the collar and so of the initial position of the needle tube being adjustable by the threaded engagement of the collar 35 with the tube, while a jam nut 109 provides for locking the collar in place. Upon forward movement of the slide 91 both the needle and needle tube 102 may interfit with the nose of the shuttle head 115, while engagement of the shuttle 40 shoulder 110 projecting from the needle tube acts to prevent further forward movement of the tube and allows the hook of the needle to be uncovered when continued forward movement produced by the slide acting through bracket 105 45 and the rear portion of the needle forces the latter to continue its forward movement.

It is also desired to uncover the hook of the needle as the latter approaches the rear end of its travel, for which purpose an abutment member 50 55 116 is provided upon brackets 46B, with which abutment the end of the needle may engage, such engagement forcing the needle forward and out of the needle tube, bracket 104 blocking forward movement of the tube at such time. The inter- 60 related functioning of these and the other parts of the machine will become more apparent with the description of the cooperating shuttle and head portions, and their operation in the performance of a tying operation.

The shuttle mechanism, although reciprocated by slide 90, is supported partly by such slide and partly by bracket 46A. The shuttle tube 111 which carries the shuttle head 115 at its end, is rotatably mounted in a bracket 112 projecting 65 from the face of the slide, and in its bearing support 114 carried by the fixed bracket 46A. The tube is slidable in the bracket bearing 114, but held against longitudinal movement with respect to the slide. In the bracket support at its rear 70 extremity the shuttle tube is slidably keyed in a 75

sleeve 118 journaled in the bracket and carrying a gear 119 by which the shuttle tube and so the shuttle may be rotated.

The construction of the tapered head 115 of the shuttle is best shown in Figures 13 to 18 inclusive, and will presently be described in greater detail with the description of the tying operation. For present purposes it is sufficient to say that it is necessary both to reciprocate and to rotate the shuttle at desired, timed intervals. 10 The reciprocating movement is imparted to the slide by cam slot 87, the cam rotating constantly and the slide moving the shuttle tube and so the shuttle longitudinally through the agency of bracket 112. Between the periods in which the 15 shuttle is required to rotate, it must be held against rotation. The intermittent rotation is derived from the main shaft 25 through gears 82 and 83, and a gear 85 which is mounted with gear 84 upon the hollow shaft 81. Gear 85 drives 20 a gear 122 carried upon the angularly disposed shaft 123. The other end of the shaft is journaled in bracket 46A and carries a mutilated bevel gear 124 meshing with the gear 126, mounted upon a stub shaft (undesignated) the 25 other end of which carries a gear 129, which in turn drives gear 119 to rotate the sleeve 118 and so the shuttle tube. The teeth of the mutilated gear are of course so spaced as to impart to the shuttle tube the desired intermittent rotation. 30

It will be seen that reciprocating motion of the shuttle is independent of its rotation, the tube 111 merely sliding in the sleeve 118. The cord for tying purposes is fed through the hollow shuttle tube from a cop 125 supported upon one end of the machine, as by bracket 127. During the retractile movement of the shuttle it is desired to pull upon the cord in order to tighten the tie formed by the machine. For this purpose gripping fingers 128, housed in a slot 130 in the 40 shuttle tube, are movable into engagement with opposite sides of the cord to grip the same, such fingers having projecting ears engageable with the inside of sleeve 118, when the shuttle tube is slid into the sleeve, such engagement acting 45 to press the fingers together to grip the cord, whereby continued rearward movement of the shuttle tube may be effective to pull upon the portion of the cord which leads to the tie. As best shown in Figures 1 and 4, the needle and 50 shuttle travel in coaxial paths beside the work, and the work tube is open in such area, in which the tie is formed. The gauge ring 23 is mounted at the top of the lower section of the work tube, merely resting or frictionally held in place upon 55 the bracket 46 and replaceable through the opening 200 between the upper and lower sections of the work tube.

The cord is carried from the shuttle about the work by means of a head 150, traveling in a 60 planetary orbit in alignment with the gap 200 in the work tube. The head, which also comprises a cutter for the cord, requires in addition to such planetary rotation, a reciprocating motion parallel to the axis of the work tube. The drive for 65 this element comprises the train of gears 140-141-142, arranged at the top of the machine and transmitting a drive from the main shaft to a hollow shaft 145 surrounding the work tube and journaled in and extending downwardly 70 from bracket 44. At its lower end, and above the tying station at the gap in the work tube, shaft 145 carries a plate 147, which rotates at a predetermined speed, carrying with it the cutting and cord-carrying head element 150. The head 75

is vertically slidable in the plate and travels in an orbit, when the plate revolves, which carries it around the work and through a transverse slot 113 in the shuttle. A spring 151 normally holds the cutting head 150 in raised position, and it will be seen upon inspection of detailed figures 10 and 11 that the head, sliding in a sleeve 152 encircling the same and projecting downwardly from the plate a lesser distance than does the head, may grip the cord, provided the latter is passed transversely through the slotted opening 155 formed in the head element 150, which is done in threading the machine.

The head is slidable into and out of the sleeve 152. Adjacent one end of the transverse slot 155, both the head and sleeve are relieved, as at 157—158, to prevent severance of the cord by shearing action in the relieved area, and allow for wedging of the cord in such area between the head and sleeve. At the other end of transverse slot 155, sharp and closely fitted surfaces are provided, which act to shear the cord when the head is urged into the sleeve by spring 151. Slot 155 lies substantially radially with respect to the axis 25 of plate 147 and of work tube, and opens forwardly as the plate revolves. It will also be seen that the orbit of the head lies substantially in the plane of the gap in the work tube which constitutes the tying station, the arrangement being such that the slot in the head may pick up the cord at the desired times, when the head is in the projected position which it occupies during a substantial part of each revolution of cam 160. When the head is to grasp the cord it is retracted 35 into the sleeve, cutting off and dropping one end of the cord and holding the other end, the latter end being then carried about the work by the head during its planetary movement.

The reciprocating motion of the head necessary to provide for severing, gripping and freeing the cord is derived from the cam 160, carried by a post 161 upstanding from the plate 147 and independently rotatable about its own axis upon the post. A gear 162, acting as a unit with and 45 to drive the cam 160, is driven through an idler gear 163 also supported from the plate 147, upon another post (164). The idler meshes with a stationary gear 165, over which it rolls as the plate rotates, gear 165 being affixed to bracket 50 44. It will be seen that an enlarged opening 167 is provided in the plate 147 to accommodate the spring 151, and the shoulder upon head 150 against which it reacts, a cap 168 closing the top of such opening and supporting the cam follower 55 170, which by engagement with the cam 160 reciprocates the head.

As best shown in Figures 13 to 18 inclusive, the cord, designated 175, is conducted through the interior of shuttle tube 111 to the shuttle head 60 115, which is also hollow and provided with a transverse cut-out opening 113 which exposes a section (spaced from the end) of the interior opening in the hollow shuttle. The cord does not extend through the cut-out portion, but passes 65 out a small opening, designated 177, through the side of the shuttle body, and longitudinally along the outside of the cut-out area of the shuttle, which may be grooved to receive such part of the cord, as best shown in Figure 15. The cord 70 turns to the interior through another small opening 178 in the nose of the shuttle, and again passes to the outside through a third small opening 179. A slot 180, extending longitudinally of the nose of the shuttle, connects the transverse 75 cut-out area 113 with the end of the shuttle.

Operation

The various elements described are so timed that the section of the cord 175 extending from the previously made tie to the shuttle is, at the commencement of each tying cycle, picked up by the head 150, which head is reciprocated by the cam 160 at the proper interval—just before the head reaches the approximate position indicated in Figures 13—to grip and hold the portion of the cord extending from the shuttle, and cut off 10 and allow to fall the portion extending from the tie. The work is then advanced by the feeding mechanism to position the work for the next tie. Thereafter the head continues its rotation, carrying the cord about the work in the manner shown 15 in Figure 14, and the shuttle and needle portions advance and interfit as shown in Figure 15. During their approach, however, the shuttle is rotated to wrap the cord about the nose, forming 20 a loop. Such rotation ceases with the transverse opening 113 in position to allow the passage laterally therethrough of the head 150, in the manner shown in Figure 15. Complete projection of the needle into the shuttle results in engagement of the end of the shuttle with the shoulder 110 carried by the needle tube 102, forcing such tube back, against the resistance of spring 103, to expose the hooked portion of the needle, while at the same time, head 150 carries the cord transversely through the opening 30 113, in such manner that the cord is guided by the inclined end of the needle, and by the back wall of the shuttle, into the hooked opening 101 of the needle. Retraction of the needle then commences, the first motion comprising pulling of the needle back into the needle tube 102. The cord is thereby gripped between the needle and needle tube, and firmly held between them by the tension of spring 103, as best shown in Figure 35 17.

The head 150 then drops the end of the cord 160, as best shown in Figure 16, and as the needle and shuttle separate, as shown in this view and in Figure 17, the cord portion so dropped is pulled by the retreating needle out of the opening 113 through the hollow interior of the shuttle and the slot 180. This, at the same time, due to extension of the cord through the slot, pulls the loop formed upon the nose of the shuttle by rotation of the latter, off of the shuttle nose, 50 while the portion held by the needle is drawn through such loop, forming the tie as a simple overhand knot.

Both the needle and the shuttle retain their hold upon the cord ends after the tie is loosely formed in the manner described, continued retraction of the shuttle resulting in gripping of the cord by the fingers 128, so that both ends of the cord are pulled tight as the needle and shuttle continue to withdraw, tightening the knot 55 and constricting the casing. The needle opens upon complete retraction, and head 150, then open, strikes the cord and frees it of the needle, as shown in Figure 18, but does not pick it up. If the cord chances to stay in the slot 155 in the head, a fixed spring finger 191 carried by and projecting upwardly from the bracket 46 strips the cord from the head, as shown in Figure 13.

Thereafter the head 150, which will be seen to make two revolutions for each tie, again returning to the position shown in Figure 13, severs the end of the cord connected to the work, retaining its hold upon the cord portion which extends from the shuttle, again pulling the cord out of the shuttle and around the work as progressively 75

shown in Figures 14 et seq., as another tying cycle commences.

- In order to allow gripping of the cord by the fingers 128 only upon sufficient retraction of the shuttle tube, bearing sleeve 118 may be counter-bored, as at 118A, (Fig. 16) to any desired extent, to prevent inward pressing of the gripping fingers until they have traveled into sleeve 118 to the depth of the counterbore. The fingers of course also grip the cord during advancing movement of the shuttle and shuttle tube, but this is without effect because such advancing movement is rapid enough to feed the cord as rapidly as it is demanded by the pull of head 150.
- While it will be apparent that the illustrated embodiment of my invention herein disclosed is well calculated to adequately fulfill the objects and advantages primarily stated, it is to be understood that the invention is susceptible to variation, modification, and change within the spirit and scope of the subjoined claims.

What I claim is:

1. Tying mechanism for relatively long and soft work, comprising a vertically disposed work-receiving portion, means for feeding work to said portion from above, and for supporting the same in depending position during tying, cord supplying means, means for carrying the cord about the work, means engageable with the ends of the section of the cord carried about the work for forming said ends into a tie, and for pulling upon at least one end thereof to tighten the tie.

2. Tying mechanism for elongated, continuous and relatively soft work, comprising a vertically disposed work-receiving member having an open area constituting a tying station, means for feeding work through said receiving member to the tying station, comprising a rotatable feed wheel by which the work is adapted to be fed downwardly into said work-receiving member, means including a shaft and tying mechanism driven thereby for forming a tie about the work at the

tying station, and means connecting said shaft to the feed wheel for actuation of the latter in timed relation to the tying mechanism, including a feed shaft, means carried thereby for supporting the feed wheel, the feed shaft being substantially at right angles to the drive shaft, geared thereto and bodily swingable about the axis of the drive shaft, means for fixing the axis of the feed shaft in various angular positions, and means for moving the supporting means for the feed wheel along the feed shaft when said shaft is swung to different positions.

3. Means as set forth in claim 1 in which said means for carrying the cord about the work includes an orbitally rotatable spring finger yieldably holding the cord spaced from the work and flexible under tension upon the cord to allow the cord to snap therefrom and move inwardly into engagement with the work.

4. Tying mechanism for relatively long and limp work, comprising in combination with a source of power and a frame, a substantially vertically disposed work-receiving portion carried by the frame, said work-receiving portion having an opening therein constituting a tying station, tying mechanism operable by said source of power for forming a tie about the work at said tying station, means arranged above said tying station for feeding the work downwardly thereto, including a movable feed member operable in timed relation to the tying mechanism, said work-receiving portion being substantially larger than the work and having an opening therein constituting the tying station and through which said means for forming the cord into a tie works, and a replaceable guide ring of substantially the diameter of the work, forming a part of the work-receiving portion adjacent the tying station, through which ring the work depends and by which it is centered in the work-receiving portion.

STEPHEN L. MATOUSEK.
